FILM FEEDING DEVICE

Charles S. Adler, New Brunswick, N. J., assignor
to Henry P. Massey, Montclair, N. J.

Application December 4, 1934, Serial No. 755,891

9 Claims. (Cl. 271—2.3)

In the process of recording or reproducing of sound (translations as it will hereinafter be called) to or from a linear film or strip, it is absolutely essential that this linear film or strip so acted upon must pass the point of translation with an even unvarying motion.

The conventional method used to bring this about is by the use of a so-called constant speed shaft upon which is affixed a sprocket, carrier or drum as well as a large balanced weighty mass. The characteristic function of this constant speed shaft is to transfer or impart the speed constant of this large weighty balanced mass to the film or strip by way of the sprocket, carrier or drum as it rotates and carries, conveys or draws the film or strip past the point of translation.

However, due to the comparative low speed of rotation of the constant speed shaft under normal operation it is essential that the weighty balanced mass attached to this shaft must be comparatively large and at times exceeding 25 lbs. in weight when extreme fidelity of translation is required.

This comparatively large weighty mass in turn necessitates the use of proportionately large component members and assemblies such as heavy supports, drives, bearings, housings, etc. This takes away from the possibilities of compactness and portability relative to quality translations in small stationary, portable and home units.

In my invention, I will show that the large balanced weighty mass and its component heavy assemblies are unnecessary and at the same time an increase in the speed constant can be had thus resulting in extremely high fidelity translation.

Referring to the drawings, Figure 1 is a front elevation of my novel film feeding device.

Figure 2 is a side elevation of the device shown in Figure 1.

Figure 3 is a top plan view of the device shown in Figure 1.

Figure 4 is a modification of my novel film feeding device.

I herewith offer a specific physical law upon which my invention is based as well as an example relative to same. This law is as follows:

The kinetic energy of a mass increases by the square of its velocity.

A mass rotating at 360 R. P. M. develops a kinetic energy of X foot pounds. The same mass rotating at 720 R. P. M. or twice the rotational speed develops a kinetic energy which has increased by the square or in other words, the

kinetic energy has increased four times with an increase of only double the R. P. M.

When said speed has been increased to 3600 R. P. M. or ten times the rotational normal speed of the constant speed shaft the kinetic energy thus developed by the rotating mass has increased by 10 squared or 100 times the kinetic energy it has developed in rotating at 360 R. P. M.

It will thus be seen that by converting speed into kinetic energy we can greatly reduce the weight of the balanced mass and its component large assemblies, for, it is the kinetic energy developed that is used to maintain, carry, convey or draw the linear film or strip past the point of translation with an even and unvarying motion.

The basic characteristics of my invention is the conversion of the kinetic energy of a small mass rotating at a high speed to a mass rotating at a lesser speed such as the constant speed shaft or carrier of a linear film or strip, descriptive details of which are as follows:

In Figures 1 and 2, I have replaced the weighty balanced mass by a spiral gear 3 which is directly attached to a standard constant speed shaft 1 upon which is also affixed the sprocket, carrier or drum 2 (sprocket shown in figure for convenience as any carrier or drum can be substituted) which in turn draws, conveys or carries the linear film or strip 6 past the point of translation which is not shown. The pinion or worm shaft 4 with its small stabilizer or flywheel 5 directly affixed couples itself by close gear meshing (as shown in this case) with spiral gear 3 whose teeth are of precision cut and proper angle so that each can act upon the other with the least degree of resistance and play.

The function of this assembly is as follows:

Constant speed shaft 1 with its affixed film sprocket, carrier or drum 2, is caused to rotate by any standard conventional means such as belt drive through pulley 7 or by synchronous chain drive through chain sprocket 8, it causes or effects shaft 4 with stabilizer or flywheel 5 that is attached thereto, to rotate at a prescribed higher speed dependent upon the ratio of the gear meshing between spiral gear 3 and worm or pinion shaft 4.

The high kinetic energy as developed by stabilizer or flywheel 5 caused to rotate at comparatively higher speed by worm or pinion shaft 4 upon which it is affixed, is imparted to spiral gear 3 through the close meshing of its teeth with worm or pinion shaft 4, this acts in turn upon the linear film or strip 6 through sprocket carrier or drum 2 by way of shaft 1, thus carrying,

conveying or drawing linear film or strip 6 with an even unvarying motion past the point of translation.

Due to the specific law I have cited above it follows that a given mass such as a stabilizer or flywheel 5 rotating at a considerably higher speed or as specific tests that were made with a ratio of 10 to 1, it was found that when stabilizer or flywheel 5 rotating at 3600 R. P. M. in mesh 10 with spiral gear 3 and shaft 1 rotating at the standard speed of 360 R. P. M., the resultant kinetic energy of a stabilizer or flywheel of but 12 ounces had brought about a resultant fidelity of translation that was superior to a mass weight of 20 lbs. when said mass weight was directly attached to the constant speed shaft 1 in place of spiral gear 3 and worm pinion shaft 4.

Because of the resultant smallness and compactness of the component members when converting speed to kinetic energy, it readily lends itself to a more direct method of drive as shown in Figure 3 wherein the linear film or strip 6 causes sprocket, carrier or drum 2 to rotate in conformity with same and which sprocket, carrier 25 or drum 2 being directly affixed to shaft 1 and spiral gear 3 causes or affects worm or pinion gear 4 with its attached stabilizer or flywheel 5 to feed or transfer back the developed kinetic energy to linear film or strip 6, thus carrying, 30 conveying or drawing same past the point of translation with an even unvarying motion.

The characteristic function is the same as the descriptions relative to Figures 1 and 2 wherein the kinetic energy of a relatively high rotating mass is imparted or transferred back to the linear film or strip 6 which motivates it.

In Figure 4, I also show the use of two stabilizers or flywheels 5 and 5A which is closely meshed to spiral gear 3. The effect of this is as above. However, it permits the use of a lesser weight stabilizer or flywheel 5 as well as overcomes any mechanical differences that may be present in spiral gear 3 and pinion or worm shaft 4.

45 What I claim as new and novel and desire to protect by patent of the United States is:

1. In a mechanism for recording or reproducing sound in which the sound record is formed on an elongated ribbon of light sensitive film and of inconsiderable mass and having a point of translation, means for progressing the ribbon past said point of translation including a rotating toothed sprocket, said ribbon being provided with spaced recesses to engage the teeth of said sprocket and ribbon progressing speed governing means including; the combination with a shaft operating at comparatively low rotative speed for driving said sprocket, of low inertia means of comparatively high rotative speed for damping speed variations of said sprocket and screw gear connecting means between said sprocket and said low inertia means, whereby the low inertia means and the sprocket are maintained in positive and continuous operative engagement.

65 2. In a mechanism for recording or reproducing sound of the type in which the sound record is formed on an elongated ribbon of light sensitive film and of inconsiderable mass and having a point of translation, means for progressing the ribbon past said point of translation including a rotating toothed sprocket, said ribbon being provided with spaced recesses to engage the teeth of said sprocket; ribbon progressing speed regulating means including the combination with a 70 shaft for driving said sprocket of comparatively

low rotative speed, of low inertia means of high rotative speed for maintaining constant the speed of said sprocket and connecting means between said sprocket and said inertia means, said inertia means including a weight of comparatively low mass fixed on a counter-shaft and said connecting means including a spiral gear connection between the counter-shaft and the shaft for driving said sprocket. 5

3. In a mechanism for recording or reproducing sound of the type in which the sound record is formed on an elongated ribbon of light sensitive film and of inconsiderable mass and having a point of translation, means for progressing the ribbon past said point of translation including a 10 rotating toothed sprocket, said film being provided with spaced recesses to engage the teeth of said sprocket; the combination therewith of a shaft for driving said sprocket, low inertia means of high rotary velocity for maintaining a constant speed of said sprocket and connecting means between said sprocket and said inertia means, said inertia means including a plurality of weights, each fixed to a counter-shaft and said connecting means including spiral gear connections between said counter-shafts and said shaft 15 for driving said sprocket. 20

4. In a mechanism for recording or reproducing sound of the type in which the sound record is formed on an elongated ribbon of light sensitive film and of inconsiderable mass and having a point of translation, means for progressing the ribbon past said point of translation including a rotating toothed sprocket, said film being provided with spaced recesses to engage the teeth of said sprocket; the combination therewith of a shaft for driving said sprocket, low inertia means of high rotary velocity for maintaining a constant speed of said sprocket and connecting means between said sprocket and said inertia means, said connecting means including close meshed spiral gearing having precision cut 30 teeth. 35

5. In a mechanism for recording or reproducing sound of the type in which the sound record is formed on an elongated ribbon of light sensitive film and of inconsiderable mass and having a point of translation, means for progressing the ribbon past said point of translation including a rotating toothed sprocket, said film being provided with spaced recesses to engage the teeth of said sprocket; the combination therewith of a shaft for driving said sprocket, low inertia means of high rotary velocity for maintaining a constant speed of said sprocket and connecting means comprising screw gears between said sprocket and said inertia means, said mechanism including means for rotating said inertia means at a substantially higher velocity than said shaft for driving said sprocket. 40 45

6. In a phonographic apparatus in which the sound record is formed on an elongated ribbon of light sensitive film and of inconsiderable mass and having feeding perforations therein, the combination of means for supporting and progressing the record ribbon from one point to another point and past an intermediate point at which the record is made on the ribbon in recording or from which the record is taken from the ribbon in reproducing under the influence of a source of light including a driven shaft having a toothed sprocket thereon, the teeth of said sprocket engaging the perforations of the ribbon, said supporting and progressing means operating at comparatively low speed, a flywheel 50 55 60 70 75

having a comparatively small mass and operating at a comparatively high rotary speed, a screw gear operatively connecting the flywheel to the driven shaft whereby the said flywheel and driven shaft are maintained in positive and continuous operative engagement and means for driving the shaft under control of said flywheel at uniformly constant speed.

7. In a phonographic apparatus in which the sound record is formed on an elongated ribbon of light sensitive film and of inconsiderable mass, the combination of means for supporting and progressing the record ribbon from one point to another point and past an intermediate point 15 at which the record is made on the ribbon in recording or from which the record is taken from the ribbon in reproducing under the influence of a source of light, said supporting and progressing means operating at comparatively low speed, a flywheel having a comparatively small mass and operating at a comparatively high rotative speed, a screw gear operatively connecting the flywheel to the ribbon supporting and progressing means whereby the said flywheel 20 and ribbon supporting and progressing means are maintained in positive and continuous operative engagement and means for driving the shaft under control of said flywheel at uniformly constant speed, said apparatus thereby arranged 25 to provide a comparatively small compact and portable device.

8. In a phonographic apparatus in which the sound record is formed on an elongated ribbon of inconsiderable mass, the combination of means for supporting and progressing the record ribbon from one point to another point and past 30

an intermediate point at which the record is made on the ribbon in recording or from which the record is taken from the ribbon in reproducing, including a driven shaft, said supporting and progressing means operating at comparatively low speed, a flywheel having a comparatively small mass and operating at a comparatively high rotary speed, a screw gear operatively connecting the flywheel to the driven shaft whereby the said flywheel and driven shaft are 10 maintained in positive and continuous operative engagement and means for driving the shaft under control of said flywheel at uniformly constant speed.

9. In a phonographic apparatus in which the sound record is formed on an elongated ribbon of inconsiderable mass, the combination of means for supporting and progressing the record ribbon from one point to another point and past an intermediate point at which the record is made on the ribbon in recording or from which the record is taken from the ribbon in reproducing, said supporting and progressing means operating at comparatively low speed, a flywheel having a comparatively small mass and operating at a comparatively high rotative speed, a screw gear operatively connecting the flywheel to the ribbon supporting and progressing means whereby the said flywheel and ribbon supporting and progressing means are maintained in positive and continuous operative engagement and means for driving the shaft under control of the said flywheel at uniformly constant speed, said apparatus thereby arranged to provide a comparatively small, compact and portable device. 35
